COMBINED BATTERY CHARGER AND EQUIPMENT CABINET

Alfred Max Hase, 6 Manorwood Road,
Scarborough, Ontario, Canada

Filed Oct. 20, 1972, Ser. No. 299,243

Term of patent 14 years

Int. Cl. D13—02

U.S. Cl. D26—15 B

FIG. 1

FIG. 4

FIG. 2

FIG. 3

FIG. 5

FIG. 1 is a perspective view of a combined battery charger and equipment cabinet showing my new design; FIGS. 2, 3 and 4 are front, side and top views respectively drawn to a smaller scale than FIG. 1;

FIG. 5 is a perspective view of the equipment cabinet as seen from the rear of FIG. 2.

I claim:

The ornamental design for a combined battery charger and equipment cabinet, as shown.
